FINGER RING OR THE LIKE

Joseph H. White and Alexander Fitzner, Chicago,
Ill., assignors to Spies Brothers, Inc., Chicago,
Ill., a corporation of Illinois

Application July 21, 1937, Serial No. 154,688

13 Claims. (Cl. 63—29)

This invention relates to a finger ring or the like and has special reference to a mounting for a finger ring, brooch, cuff link or similar article of jewelry which is provided with an interchangeable or detachable plate adapted to carry a monogram, emblem, stone, or other decorative member.

More particularly this invention relates to a mounting having a seat with a plate adapted to carry a stone, monogram, emblem, or the like, for engaging the seat, there being means fixed against movement on the mounting and on the plate for detachably securing the plate on the seat operable in its securing or detachable engagement by a relative rotative movement between the plate and seat.

The present invention contemplates the provision of a novel detachable or interchangeable setting or plate for mountings for finger rings, brooches and similar articles of jewelry with a novel construction of means for locking the plate to the mounting to which it is applied in a secure manner so that accidental displacement or removal of the same is eliminated.

It is desirable for jewelers, in order to alleviate to a great extent the expense of carrying a very substantial stock, to carry a mounting of fixed design which may be ornamented to the individual taste of a prospective buyer by one of many plates carrying the desired monogram, emblem, jewel, or other decorative member. For example, the band of a finger ring or the shape of the mounting of a brooch or cuff link may meet with the approval of a great number of individual tastes, whereas the color of the stone to be fixed to the mounting may vary as greatly as the number of the prospective purchasers. Then again, a prospective purchaser may desire several differently colored stones in keeping with the various ensembles of the individual's wardrobe, or may have only temporary use for the plate be it a high school class ring or fraternal emblem for wear prior to eligibility to wear a college insignia, and it would be most desirable and would minimize expense to have a single mounting capable of interchangeably supporting any one of the group of stones or other decorative members desired to be worn.

It is, therefore, an object of this invention to provide a mounting which is adapted to interchangeably carry one of a number of stones, signets, or emblems or a combination thereof so that a substantial number of differently decorative effects may be obtained at a minimum of expense. The jeweler likewise may carry a stock meeting the demands of a maximum number of individuals at a minimum of expense. Further, the manufacturer may employ the constructions as samples to the trade to minimize expense in

that connection, utilizing but a minimum number to obtain a maximum of desired effects.

In providing the individual with interchangeable decorative units for a single mounting, it is further desirable that no mechanical assistance be necessary in interchanging the members on the mounting. The present invention has for another of its objects the provision of a mounting in which a locked or secured position is obtained by a movement of the member to be locked or secured. Applicants have knowledge of prior art constructions and patents wherein the locking means employ a wrench or a key to lock the decorative member to the mounting. This ordinarily requires more than the usual skill of the wearer and is objectionable in that respect, and, further, that the key or wrench may become displaced or lost occasioning inconvenience even though the wearer had the skill necessary to lock the separable members.

Applicants also have knowledge of prior art constructions and patents wherein interchangeability of the members is restricted to the shape of the mounting as, for example, the mounting may have a chamber or recess of a peculiar shape for receiving a setting or decorative member of that shape. The present invention overcomes this objection and it is, therefore, a further object of this invention to provide a mounting having a substantially flat seat at least over the peripheral portion thereof on which is engaged a substantially flat portion of the setting or decorative member. In this event, it is not necessary for each individual setting to be precisely the same contour and the settings, therefore, may vary in outline as desired.

Other objects and advantages of this invention will hereinafter be more particularly pointed out and for a more complete understanding of the characteristic features of this invention, reference may now be had to the following description when taken together with the accompanying drawing, in which latter:

Figure 1 is a perspective view of a finger ring embodying the features of this invention;

Fig. 2 is a front elevational view of the mounting of the finger ring shown in Fig. 1;

Fig. 3 is a rear elevational view of the detachable plate member or setting shown in Fig. 1, the views shown in Figs. 2 and 3 showing engaging surfaces of the mounting and setting respectively;

Fig. 4 is a plan view of a fragmentary portion of Fig. 2;

Fig. 5 is a sectional view taken on the line 5—5 of Fig. 3;

Fig. 6 is a fragmentary sectional view taken on the line 6—6 of Fig. 2, showing the detachable plate or setting in position on the mounting; and

Fig. 7 is a view similar to Fig. 2 showing a modified form of construction embodying the features of this invention.

Referring now to the drawing, and more particularly to Figs. 1 to 6 inclusive thereof, the invention is shown as comprising an annular band 10 having a substantially rectangular enlargement 11 on one side thereof with a substantially flat seat 12 at least over the peripheral portion thereof. In the present illustration, the substantially flat seat extends over the entire area of the face of the enlargement 11 although, of course, it is to be understood that it is desirable merely that a peripheral portion thereof may be substantially flat.

An auxiliary plate 13 is mounted on the face of the enlargement 11 and is secured thereto preferably by means of pins 14 extending through the plate and through the enlargement 11 although, of course, the plate may be soldered or otherwise secured thereto. The auxiliary plate 13 is provided with opposed fingers 15 extending from the ends of the plate in opposite directions. In the instance of the drawing, the fingers 15 are formed integrally with the auxiliary plate 13 and extend flush with the outer surface thereof and, further, being of substantially less depth than the auxiliary plate 13, provide clearance between the fingers and the seat 12. The plate 13 and extending fingers 15 are preferably formed of spring metal and preferably of a non-corrosive metal such as stainless steel.

A plate 16 of substantially the same shape as the enlargement 11 is provided with a central recess 17 of substantially rectangular outline, the portion of the material bounding the smaller ends of the rectangular recess being arcuate and undercut to provide oppositely disposed ledges 18 which extend in a direction toward each other and are provided with notches 18a in the faces thereof. The ledges are cut away at opposite ends to provide recesses 19 communicating with the undercut portion forming the ledges 18 to receive the fingers 15 as will hereinafter be more fully apparent.

When it is desired to secure the plate 16 on the mounting, the plate 16 is disposed angularly relative to a normal assembled position thereof in such a manner that the slots or recesses 19 register with the fingers 15, the fingers being of such a width as will conveniently pass through the slots 19. A relative rotative movement between the plate 16 and the mounting will cause the spring fingers 15 to engage the ledges 18 for snap engagement with the notches 18a in the faces thereof, the ledges occupying a position in the space between the fingers and the seat 12.

It is preferable to obtain a frictional engagement between the fingers 15 and ledges 18 in the manner above noted or in the provision of cam surfaces or the like when in a normal assembled position so that a secured relation may be had to guard against accidental displacement. Also, in order to properly predetermine the normal assembled position of the removable plate 16 with respect to the mounting, stop members are provided preferably integrally with the respective members, the side walls bounding the recess 17 engaging the side walls of the auxiliary plate 13.

It will be noted that the contour of the auxiliary plate 13 is polygonal and is preferably of substantially the same size and shape as the recess with the exception that the corners are cut off to provide angularly disposed sides 20 relative to the straight sides 21. When disposing

the detachable plate 16 on the mounting, the side walls bounding the recess 17 lie adjacent the side walls 20 of the auxiliary plate 13 and the fingers 15 are received in the recesses or slots 19. A relative rotative movement between the plate 16 and the mounting moves the fingers 15 into snap engagement with the notches 18a of the ledge 18 until the side walls bounding the recess 17 engage the side walls 21 of the auxiliary plate 13, the side walls 21 acting as a stop to predetermine the normal assembled position of the members.

The plate 16 may be provided with any type of decorative member or members and, as shown, a stone 22 is received in an outer recess in the plate and secured thereto in any desired manner, the stone having a signet 23 attached thereto.

The detachable plate 16 is thus detachably secured to the mounting merely by a relative rotative movement therebetween, thus eliminating mechanical assistance in the form of keys or wrenches. The simplicity of the locking means is very desirable since the operation thereof may be performed by those unskilled in mechanical manipulation. Also, aside from the simplicity of the operating parts, it does not require outside assistance in the form of tools which may become displaced or inconvenient to use.

Referring now more particularly to Fig. 7 of the drawing, a mounting is therein shown comprising an annular band 10a having an enlargement 11a with a substantially flat seat 12a over the face thereof. A plate 13a is suitably secured as by means of pins 14a to the enlargement 11a on the face of the seat 12a thereof and is provided with fingers 15a for the same purpose as that previously described with reference to the same numerals. In this instance, the auxiliary plate 13a is centrally recessed and the face of the seat 12a is likewise recessed in registration therewith should it be desirable to provide a stone or the like carried by a plate member which stone would project to a depth greater than that of the plate member and face of the enlargement.

The present mounting is oval in form and may readily receive a similarly contoured member or, since the peripheral surface is flat, any member of any shape having the locking characteristics previously described with reference to the first embodiment.

While but two embodiments of this invention are herein shown and described, it is to be understood that various modifications thereof may be apparent to those skilled in the art without departing from the spirit and scope of this invention and, therefore, the same is only to be limited by the scope of the prior art and the appended claims.

We claim:

1. In a jewelry mounting having a substantially flat seat at least over the peripheral portion thereof, a plate adapted to carry a stone, signet or the like having a substantially flat portion for engaging said seat, and means disposed outwardly of the plane of said seat for detachably securing said plate on said seat, said securing means being operated to secure and to detach said plate to and from said seat respectively by a relative movement between said plate and seat.

2. In a jewelry mounting having a substantially flat seat at least over the peripheral portion thereof, a plate adapted to carry a stone, signet or the like having a substantially flat portion for engaging said seat, and means on said

plate cooperating with means on said mounting for detachably securing said plate on said seat, said cooperating means being disposed outwardly of the plane of said seat and being operated to 5 secure and to detach said plate to and from said seat respectively by a relative movement between said plate and seat.

3. In a jewelry mounting having a substantially flat seat at least over the peripheral portion thereof, a plate adapted to carry a stone, signet or the like having a substantially flat portion 10 for engaging said seat, and resilient means on said plate engaging cooperating means on said mounting for detachably securing said plate on 15 said seat, said resilient means and said cooperating means being disposed outwardly of the plane of said seat and being operated to secure and to detach said plate to and from said seat respectively by a relative movement between said plate 20 and seat.

4. In a jewelry mounting having a substantially flat seat at least over the peripheral portion thereof, a plate adapted to carry a stone, signet or the like having a substantially flat portion for 25 engaging said seat, and members having snap engagement therebetween and disposed on said mounting and said plate for detachably securing said plate on said seat, said snap engaging members being disposed outwardly of the plane of said 30 seat and being operated to secure and to detach said plate to and from said seat respectively by a relative rotative movement between said plate and seat.

5. In a jewelry mounting having a seat, a plate 35 adapted to carry a stone, signet or the like for engaging said seat, and means fixed against movement on said mounting and on said plate for detachably securing said plate on said seat, said fixed securing means being operated to secure and 40 to detach said plate to and from said seat respectively by a relative rotative movement between said plate and seat.

6. In a jewelry mounting having a seat, a plate adapted to carry a stone, signet or the like for engaging said seat, said plate having a fixed ledge 45 extending therefrom, and means fixed against movement projecting from said mounting for engaging said ledge for detachably securing said plate on said seat, said ledge and projecting 50 means being operated to secure and to detach said plate to and from said seat respectively by a relative rotative movement between said plate and seat.

7. In a jewelry mounting having a seat, a plate 55 adapted to carry a stone, signet or the like having a portion for engaging said seat, said plate having fixed opposed ledges extending in a direction toward each other, and opposed fingers immovable on said mounting extending in a direction away 60 from each other for engaging said ledges for detachably securing said plate on said seat, said ledges and fingers being operated to secure and to detach said plate to and from said seat respectively by a relative rotative movement between said plate and seat.

8. In a mounting having a seat, a plate adapted to carry a stone, signet or the like having a portion for engaging said seat, said plate having opposed ledges adjacent recesses communicating 70 therewith, and opposed fingers on said mounting extending in a direction away from each other

for engaging said ledges through said recesses for detachably securing said plate on said seat, said fingers and ledges being operated to secure and to detach said plate to and from said seat respectively by a relative rotative movement 5 between said plate and seat.

9. In a jewelry mounting having a substantially flat seat at least over the peripheral portion thereof, a plate adapted to carry a stone, signet or the like having a substantially flat portion 10 for engaging said seat and being wholly contained in a plane outwardly of said seat, said plate having a ledge adjacent a communicating recess, and a finger immovably secured on said mounting for engaging said ledge through said recess for detachably securing said plate on said seat, said ledge and finger being operated to secure and to detach said plate to and from said seat respectively by a relative rotative movement 15 between said plate and seat. 20

10. In a jewelry mounting having a substantially flat seat at least over the peripheral portion thereof, a plate adapted to carry a stone, signet or the like having a substantially flat portion for engaging said seat, said plate lying wholly 25 outside of the plane of said seat and having a central recess with opposed apertured ledges extending into said recess, and an auxiliary plate of spring metal secured to said mounting and having fingers extending therefrom adapted to be inserted through the apertures of said ledges when said first mentioned plate and mounting are angularly disposed relative to a normal assembled position thereof, said auxiliary plate lying within the recess of said first mentioned plate and said 30 fingers frictionally engaging said ledges in a normal assembled position. 35

11. In a jewelry mounting having a seat, a plate adapted to carry a stone, signet or the like having a portion of non-circular contour engaging said 40 seat, said plate having a recess therein, and a finger on said mounting adapted to be inserted through said recess when said plate and mounting are angularly disposed relative to a normal assembled position thereof, and means on said plate 45 for frictionally engaging said finger in a normal assembled position.

12. In a jewelry mounting having a seat, a plate adapted to carry a stone, signet or the like having a portion of non-circular contour engaging said 50 seat, said plate having a recess therein, and a finger on said mounting adapted to be inserted through said recess when said plate and mounting are angularly disposed relative to a normal assembled position thereof, means on said plate 55 for frictionally engaging said finger in a normal assembled position, and stop means for predetermined said normal assembled position.

13. In a jewelry mounting having a seat, a plate adapted to carry a stone, signet or the like having a portion of non-circular contour engaging said seat, said plate having a recess therein, and a finger on said mounting adapted to be inserted through said recess when said plate and mounting are angularly disposed relative to a normal 60 assembled position thereof, and a ledge on said plate for frictionally engaging said finger in a normal 65 assembled position.

CERTIFICATE OF CORRECTION.

Patent No. 2,108,324.

February 15, 1938.

JOSEPH H. WHITE, ET AL.

It is hereby certified that error appears in the printed specification of the above numbered patent requiring correction as follows: Page 3, first column, line 58, claim 7, for "immovable" read fixed against movement; line 66, claim 8, before "mounting" insert jewelry; line 68, same claim, after "having" insert fixed; line 70, same claim 8, after "fingers" insert immovable; and that the said Letters Patent should be read with these corrections therein that the same may conform to the record of the case in the Patent Office.

Signed and sealed this 29th day of March, A. D. 1938.

Henry Van Arsdale,
Acting Commissioner of Patents.
